BIBB SEATING TOOL

Roland G. Hawker, Burlington, Vt.

Original application September 6, 1935, Serial No. 39,589. Divided and this application January 19, 1938, Serial No. 185,782

10 Claims.

(Cl. 90—12.5)

This invention relates to valve tools which are particularly adapted for renewing the seating surfaces of ball cock valves and analogous constructions and performing various operations on valve closures. This is a division of my copending application Serial No. 39,589, filed September 6, 1935.

The present tool is applicable to a wide range of sizes of valves, with which it is detachably engageable by means of a universal mounting or an adapter therefor. Such mounting forms a guide for a revoluble cutter or other tool supporting shaft, and includes manually adjustable means for positively feeding the shaft and cutter or other tool carried thereby axially independently of its rotation.

Ball cock type valves have presented a problem of long standing without anyone ever producing a reseating tool that has been acceptable to the public. The valve seat is oftentimes obscurely positioned, or the surrounding fixtures are such that they cannot be engaged successfully by adapters now on the market. It is well known likewise that such surrounding fixtures vary in contour, and that practically no two valves have the same surroundings. That being the case, it becomes essential to have an adapter which is universally adaptable.

The object of the invention is to simplify the structure as well as the means and mode of operation of such devices whereby they will not only be cheap in construction, but will be more efficient and convenient in use, accurate in operation, uniform in action, easily operable and unlikely to get out of repair.

A further object of the invention is to provide an improved form of mounting for the tool and to provide positive feeding means for the tool supporting and operating shaft.

A further object of the invention is to provide adapters by which the range of adaptation may be greatly extended to include valves of extreme sizes.

A further object of this invention is to provide an expansible and contractible adapter unit for use with various sizes and types of valves.

Another object of this invention is to provide an adapter for removing obstacles from portions of the valve fixture.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawing.

In the accompanying drawing, wherein is shown the preferred but obviously not necessarily the only forms of embodiment of the invention, Fig.

1 discloses an adapter particularly adapted for use with ball cock attachments and illustrated with a drill attachment for removing a screw or other obstructions from a portion of the valve fixture. 5

Fig. 2 is similar to Fig. 1 showing the attachment engaging a ball cock valve.

Figs. 3, 4, 5, 6, 7 and 8 show parts of the adapters shown in Figs. 1 and 2, Figs. 5 and 6 having portions shown in section. 10

Like parts are indicated by similar characters of reference throughout the several views.

In the accompanying drawing, 1 indicates a typical ball cock valve casing embodying a bore or opening 2 in which is located a valve seat 3 15 to be formed or refinished and with which a valve such as shown at 4 (Fig. 1) cooperates to close or open the valve passage by axial movement through rotation and effect of a threaded portion 5 as is well known in the art. The present valve seating device is detachably engageable with a valve (Fig. 1) or with the opening or bore 2 in which the valve reciprocates (Fig. 2).

The device consists of a stem 6, which has an operating handle 7 on its uppermost end and 25 extends downwardly through and is freely rotatable in an externally threaded sleeve 8. The stem 6 normally is longitudinally movable a restricted distance in the sleeve 8 and is normally held against other than restricted longitudinal 30 movement with relation to the sleeve 8 by a collar 9 held in selected position on the stem 6 by a screw 10 and having a depending portion 11 including a cavity 12 in which a collar 13 on the uppermost end of the sleeve 8, of greater diameter 35 than the opening to the cavity, is disposed, the collar 13 being of less thickness than the depth of the cavity 12 as shown in Figs. 1 and 2. With such construction, the stem 6 may freely rotate in the sleeve 8 but may not move longitudinally 40 relative to the sleeve except for a restricted distance or upon loosening of the screw 10 and adjustment of the stem 6 relatively to the collar 9. The threaded sleeve 8 has an enlarged annular knurled grip 14 on its uppermost end for a purpose hereinafter apparent. 45

Upon the threaded sleeve 8 is mounted an internally and externally threaded tubular member 15, the internal threads of the member engaging the external threads of the sleeve 8. The external threads of the tubular member 15 provide for the mounting of an internally threaded annular member 16 which, as shown, has a flaring angularly disposed skirt portion made up of sectors 17 separated by notches 18. 50

Secured to the lowermost end of the tubular member 16 by means of a suitable key 19 is a frusto-conical shaped member 20 made up of interconnected sectors 21 separated by notches 22 which are angularly disposed as shown in Fig. 60

1 and extend from top to bottom of the member. The key 19 extends from the frusto-conical shaped member 20 into an annular channel 23 in the lowermost end of the tubular member 15, which permits free rotative movement of the frusto-conical shaped member 20 with relation to the tubular member 15.

5 A plurality of grippers 24 which take the form of elongated bar-like members rest within each of the respective aligned notches 18 and 22 in the member 16 disposed at the top of the tubular member 15 and the frusto-conical disc member 20 secured to the bottom of the tubular member 15 respectively, the gripper bars being thus angularly 10 disposed with their lowermost ends converging toward each other. In order that the bar-like gripping members 24 may move with movement of the member 16, the gripping members 24 are provided with reduced portions 25, formed by oppositely disposed notches 26, which rest within the notches 18 of the member 20. To hold the grippers 24 in such position that they will lie within the angularly disposed notches 22 in the frusto-conical members 20, a frusto-conical sleeve 27 is provided, the sleeve having interior threads 28 which cooperate with exterior threads 29 on the frusto-conical member 20. By drawing the frusto-conical member 27 further into the frusto-conical member 20, the space between the inner 15 and outer surfaces of the respective members is obviously reduced. It is preferable that such space between the members 20 and 27 be sufficient to permit the longitudinal movement of the assembled members 20 and 27 relative to the bar-like gripping members 24 as a result of adjustment of the threaded sleeve 8 upwardly or downwardly with respect to the gripper bar supporting member 16, but insufficient to permit excessive movement thereof whereby to accurately center 20 the cutter or other tool with respect to the valve fixture. In order to maintain the desired position of the frusto-conical member 27 with respect to the frusto-conical member 20, the member 27 is provided with a slot 30 in which a set screw 31 engaging a suitable aperture in the frusto-conical member 20 is engaged. By tightening the set screw, any desired adjustment of the frusto-conical member 27 with respect to the frusto-conical member 20 may be maintained.

25 Referring to Figs. 1 and 2, it is illustrated that the tool is adapted for use either in combination with a drill 32 or like device for removing screws and other foreign obstacles from portions of the valve fixture, or in combination with a cutter 33 for primarily forming, or re-forming, a valve seat 34 for proper functioning with a valve closure. The stem 6 is preferably provided with a threaded end (not shown) whereby the particular tool desired to be used with the device and having the requisite threaded opening may be selectively assembled therewith.

30 Considering operation of the device in connection with a valve closure 4 as shown in Fig. 1, by turning the tubular sleeve 15 by means of the knurled flange portion 34 provided for the purpose, and which turns the tool and the tubular sleeve 8 relatively to the members 16 and 20 when the member 16 is held against rotation, the frusto-conical members 20 and 27 which rotate freely 35 with relation to the tubular sleeve 15 are drawn closer to or moved further away from the notched member 16 in which the bar-like gripping members 24 are supported. Due to the angular disposition of the bar-like gripping members 24 and the angularly disposed notches 22 in the frusto-

40 conical member 20, such relative movement of the members 16 and 20 toward and away from each other results in a corresponding approach or separation of the lowermost ends of the bar-like gripping members 24 toward or away from each other. Thus, to engage the valve closure 4 as shown in Fig. 1, the members 16 and 20, which have been initially positioned relatively apart from each other in order to separate the lowermost ends of the bar-like gripping members 24 are 45 moved toward each other by rotation of the threaded sleeve 15, the sleeve 8 and the tool, relatively to the member 16 in which the bar-like gripping members 24 are supported. Relative approach movement of the members 16 and 20 moves the lowermost ends of the bar-like gripping members 24 gradually toward each other until they engage and rigidly grip the valve closure 4 therebetween. Having thus gripped the valve closure, the next step is rotative adjustment of the sleeve 8 relatively to the tubular member 15 to bring the tool 32 carried by the lowermost end of the stem 6 into operative engagement with the valve closure 4. Having been moved into operative position with respect to the valve closure 4, the tool can be operated by rotation of the stem 6 with relation to the sleeve 8, the stem 6 having linear movement corresponding to the depth of the cavity 12 with relation to the thickness of the shoulder 13. As hereinbefore described, any further desired longitudinal adjustment of the stem 6 with relation to the sleeve 8 can be made by loosening the screw 10 and adjusting the collar 9 and associated parts relatively to the stem 6. Having completed the desired operation with the 50 device, the members 16 and 20 are moved relatively away from each other for reversal of the operation set forth in producing gripping engagement of the members 24 with the valve closure 4, which will result in separation movement of the lowermost ends of the gripping members 24 and release of their engagement with the valve closure 4.

55 In Fig. 2 of the drawing is illustrated application of the device to a valve fixture of the ball cock type for the purpose of forming, or re-forming, the valve seat 3 with which the valve closure cooperates. In such application of the device, the stem 6 carries a cutter 33, preferably of the type disclosed in my copending application, Serial No. 39,589, of which this is a division, which is disposed below the lowermost ends of the bar-like gripping members 24. To assemble the device with the valve fixture, the members 16 and 20 are first moved into such relatively close position as to engage the stem 6. Then, the device is disposed in relation to the valve body in such position that the gripping surfaces 35 and 36 are opposite those surfaces of the valve fixture which it is desired to grip. At 60 such time the members 16 and 20 are moved toward separated position by rotation of the sleeve 15 and associated parts relatively to the member 16, which will result in spreading of the lowermost ends of the bar-like gripping members 24 until either the selected surface 35, or the selected surface 36, of each bar-like gripping member is in gripping engagement with the selected surface of the valve body. Following this, the stem 6 is rotated in the sleeve 8 and adjusted as hereinbefore described for the purpose of rotating the cutter 33 relatively to the valve seat 3, and the device may be removed from the valve fixture by a reversal of the operations just described.

65 From the above description it will be apparent

ent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A universal mounting device for a valve seating tool engageable with a valve fixture comprising a tapered body portion having a plurality of channels in the tapered portion, gripper jaws 25 one in each channel having a longitudinal movement to engage the work internally, and means having a longitudinal movement with respect to the tapered body portion for moving the jaws in said channels, said means including a member 30 having flared sectors spaced to form slots engaging the ends of said clamping jaws.

2. In a mounting and supporting member for a valve tool, a tool supporting and operating shaft, a sleeve in which the shaft is mounted for longitudinal and free rotative movement, means for restricting longitudinal movement of the shaft relative to the sleeve, and means associated with the sleeve for securing the tool in operative position with respect to the valve including individual members movable by a single instrumentality longitudinally for approach and separation thereof to engage or release the valve.

3. In a mounting and supporting member for a valve tool, a tool supporting and operating shaft, a sleeve in which the shaft is mounted for free rotative movement, and means associated with the sleeve for securing the tool in operative position with respect to the valve including individual members movable by a single instrumentality longitudinally for approach and separation thereof to engage or release the valve.

4. In a mounting and supporting member for a valve tool, a tool supporting and operating shaft, a sleeve in which the shaft is mounted for longitudinal and free rotative movement, means for restricting longitudinal movement of the shaft relative to the sleeve, said last named means being selectively operable to permit unrestricted longitudinal adjustment of the shaft relative to the sleeve, and means associated with the sleeve for securing the tool in operative position with respect to the valve including individual members movable by a single instrumentality longitudinally for approach and separation thereof to engage and release the valve.

5. In a mounting and supporting member for a valve tool, a tool supporting and operating shaft, a sleeve in which the shaft is mounted for free rotative movement, means associated with the sleeve for securing the tool in operative position relative to the valve including individual gripper members movable longitudinally for approach and separation thereof to engage and release the valve, a sleeve supporting the gripper

members and adjustably mounted on the first named sleeve and with respect to which the first named sleeve is adjustable to position the tool with respect to operative relation with the valve.

6. In a mounting and supporting member for a valve tool, a tool supporting and operating shaft, a sleeve in which the shaft is mounted for free rotative movement, means associated with the sleeve for securing the tool in operative position relative to the valve including individual gripper members movable longitudinally for approach and separation to engage and release the valve, a sleeve supporting the gripper members and adjustably mounted on the first named sleeve and with respect to which the first named sleeve is adjustable to position the tool with respect to operative relation with the valve, said second named sleeve having guiding means for the individual gripper members associated therewith.

7. In combination with a valve tool having a supporting and operating shaft, a member associated with the shaft and with respect to which the shaft and tool are rotatable and longitudinally adjustable, and means carried by the member for securing the tool in operative position with respect to the valve including individual members movable by a single instrumentality longitudinally for separation and approach to engage and release the valve.

8. In combination with a valve tool having a supporting and operating shaft, a member associated with the shaft and with respect to which the shaft and tool are rotatable and longitudinally adjustable, and means carried by the member for securing the tool in operative position with respect to the valve including individual members movable by a single instrumentality longitudinally for separation and approach to engage and release the valve, and means associated with the first named member for supporting and moving the gripping members in unison into and out of engagement with the valve independently of movement with the shaft and tool supported thereby.

9. In combination with a valve tool having a supporting and operating shaft, a member associated with the shaft and with respect to which the shaft and tool are rotatable and longitudinally adjustable, means carried by the member for securing the tool in operative position with respect to the valve including gripping members movable by a single instrumentality longitudinally for separation and approach to engage and release the valve, and relatively movable means carried by the member for supporting, guiding, and moving the gripping members longitudinally into and out of engagement with the valve.

10. In combination with a valve tool having a supporting and operating shaft, a member associated with the shaft and with respect to which the shaft and tool are rotatable and longitudinally adjustable, means carried by the member for securing the tool in operative position with respect to the valve including gripping members movable longitudinally for separation and approach to engage and release the valve, and relatively movable means carried by the member and movable independently of movement of the shaft and tool supported thereby for supporting, guiding, and longitudinally moving the gripping members into and out of engagement with the valve.

ROLAND G. HAWKER.
